COMPOUNDS OF THE CYCLOPENTANO-POLYHYDROPHENANTHRENE SERIES AND PROCESS OF MAKING SAME

Tadeus Reichstein, Basel, Switzerland

No Drawing. Application January 12, 1943, Serial No. 472,153. In Switzerland April 15, 1942

7 Claims. (Cl. 260—397.1)

In patent application Serial No. 433,072, filed March 2, 1942, a process is described for the manufacture of compounds of the cyclopentano-polyhydrophenanthrene series which are substituted in ring A and unsaturated in ring C. The compounds of the androstane and pregnane series which are used as starting products in this process can be obtained, for example, by degrading the side chain of the corresponding compounds of the cholic acid series, which are substituted in the 12-position by a free or esterified hydroxyl group, or their lower homologues.

It has now been found that similar compounds of the cyclopentanopolypolyhydrophenanthrene series with an unsaturated ring C, as in the above patent, can be obtained by degradation of the side chain of compounds of the cholic acid series, which are substituted in ring A and unsaturated in ring C, their lower homologues or their stereoisomers, by an already known method.

Particularly suitable starting products are compounds of the cholic acid series unsaturated in ring C, such as are obtained, as described in the above patent, from corresponding compounds which have a free or esterified hydroxyl group in the 12-position and also, for example, a further free or substituted hydroxyl or carbonyl group in the 3 and/or 7 position. Besides the double bond in ring C they may be saturated or unsaturated in the nucleus, completely or partly esterified and, in addition, of any steric configuration. The following compounds can, for example, be used: $\Delta^{11:12}$ -3-hydroxy-cholenic acid, $\Delta^{11:12}$ -3-keto-cholenic acid, $\Delta^{11:12}$ -3:7-dihydroxy-cholenic acid, $\Delta^{5:6,11:12}$ -3-hydroxy-choladienic acid, $\Delta^{5:6,11:12}$ -3:7-di-hydroxy-choladienic acid, $\Delta^{4:5,11:12}$ -3:7-diketo-choladienic acid, the corresponding derivatives esterified in the hydroxyl and/or acid groups, and analogous compounds unsaturated in the 9:11-position or another position in ring C. The lower homologues of the above acids, such as are obtained, for example, from the above process by only partial degradation of the side chain, can also be used.

The side chain is degraded directly or in stages by a method already known per se. If carried out in stages, the so-called Wieland's process can very satisfactorily be used, i. e. the acids or esters used as starting products are converted by means of an organic-metallic compound into the corresponding tertiary carbinols, which are then oxidized, if desired after transforming them into the ethylene compounds. In this way the next lowest homologous acids, or the pregnane or androstane compounds, are obtained. This treatment is repeated with the acids which may be obtained until the pregnane or androstane compounds (17-ketones or 17-carboxylic acids) are formed. The pregnane compounds may also be subsequently converted, if required, into the corresponding

androstane compounds, by an already known method.

The initial acid compounds can also be subjected to, other known gradual degradation methods, for example, the Curtius' or Hofmann's degradation. Otherwise the degradation can be effected by radical oxidation, for example by means of a hexavalent chromium compound, a permanganate, a peroxide or one of the other oxidizing agents, known for this reaction. In this case the acid and neutral degradation products of the androstane series are obtained in addition to the compounds of the pregnane series in one operation. Finally the degradation processes may be combined.

Sensitive substituents such as hydroxyl groups, keto groups or double bonds are if necessary temporarily protected in a known manner during the various degradation reactions, the first preferably by acylation, the last by addition of halogen or hydrogen halide.

The products of the process under consideration are therapeutically valuable substances or may be converted into such.

The following examples illustrate the invention, but are not to be regarded as limiting it in any way:

Example 1

$\Delta^{11:12}$ -3-acetoxy-cholenic acid methyl ester, M. Pt. 117-118° C. (obtained according to patent application Serial No. 433,072) is converted into 11:12-dibrom-3-acetoxy-cholenic acid-methyl-ester by dropping in a solution of bromine in acetic acid. 1 g. of the dibrom compound is dissolved in 30 c. c. glacial acetic acid (stable to chromic acid) and a solution of 1 g. chromium trioxide in 1 c. c. of water and 3 c. c. of glacial acetic acid added at 75° C. over a period of 30 minutes, stirring continually. Stirring is continued for 4 hours and the temperature kept at about 70° C. The green solution is evaporated down to a syrup in vacuo at 30-40° C., the residue dissolved in water and the solution thoroughly extracted three times with ether. The ether solutions are washed several times with 10 per cent. sulphuric acid, saturated aqueous bicarbonate solution, and water. After evaporating down the ether solution, the residue is dissolved in 95 per cent. acetic acid and the bromine eliminated by vigorously stirring the solution with zinc dust for 10 hours at room temperature. The acetic acid solution is filtered off by suction, diluted with much water and extracted with ether. The ether solution is then washed with water, extracted with aqueous soda solution, dried and evaporated.

Some pure starting product is regenerated from this neutral fraction by re-crystallizing from methyl alcohol. The mother liquors are boiled under reflux with 3 c. c. of 10 per cent. potas-

sium hydroxide in methyl alcohol for 2 hours. Subsequent separation gives a neutral fraction which yields a ketone fraction by separation with the chloride of trimethyl-ammonium acetic acid hydrazide. The latter fraction is separated chromatographically, using standardized aluminium oxide. In this way the $\Delta^{11:12}$ -3-hydroxy-androsten-17-one and the $\Delta^{11:12}$ -3-hydroxy-pregnene-20-one are obtained. These two compounds have the following constitutional formulas:

The acid degradation products are isolated by acidifying the soda solutions and extracting with the ether. The ether residue is boiled for 2 hours with a 50 per cent. aqueous solution of potassium hydroxide. The mixture is then acidified, thoroughly extracted three times with ether, the ether solution washed with water, dried, and a diazomethane solution added until a permanent yellow colouration is obtained. After 10 minutes the majority of the ether is evaporated, the remaining solution washed with dilute hydrochloric acid, soda solution and water, dried and evaporated down. The methyl-ester mixture thus obtained is partially saponified by boiling for 15 minutes with a 5 per cent. solution of potassium hydroxide in methyl alcohol. After cooling, water is added, the methyl alcohol distilled off in vacuo at 35° C. and the residue twice extracted with ether. The ether solution is again washed with some caustic soda solution and water, dried and evaporated down. The fraction of the difficultly saponifiable ester thus obtained is boiled under reflux with 10 per cent. potassium hydroxide in methyl alcohol for 20 hours, diluted with water, the methyl alcohol evaporated, the residue extracted three times with ether and the ether solution washed several times with water and a little caustic soda solution. The alkaline portions are acidified and extracted with ether and the ether residue esterified with diazomethane. In this way $\Delta^{11:12}$ -3-hydroxy-*etio*cholenic-acid-methyl-ester is obtained with the following formula:—

This compound melts at 124-126° C. and has a specific rotation of

$$[\alpha]_D^{25} = +77^\circ$$

(in acetone). The acetate of this compound forms, on recrystallization from petroleum ether, 75

needles melting at 99-100° C. and has a specific rotation

$$[\alpha]_D^{25} = +89^\circ$$

5 (in acetone). By dehydration of the $\Delta^{11:12}$ -3-hydroxy-*etio*cholenic-acid-methyl-ester, with aluminium isopropylate in the presence of cyclohexanone, $\Delta^{11:12}$ -3-keto-*etio*cholenic-acid-methyl-ester, empirical formula $C_{21}H_{30}O_3$ (described in patent application Serial No. 433,072) is obtained. It melts in the pure state at 136-138° C. and has a specific rotation

$$[\alpha]_D^{25} = +79^\circ$$

15 (in acetone).

Instead of chromic acid for example another hexavalent, chromium compound, a permanganate or hydrogen peroxide may be used for the radical degradation.

20

Example 2

See formulas on pages 3 to 5.

(a) The solution of 6.3 g. $\Delta^{11:12}$ -3-hydroxy-*cholenic-acid-methyl-ester*, melting at 102° C. (Formula I, obtained by partial saponification of

25 $\Delta^{11:12}$ -3-acetoxy-*cholenic-acid-methyl-ester*, M. Pt. 117-118° C., which is used in Example 1 as starting product, by means of a 1 per cent. solution of hydrogen chloride in methyl alcohol) in 30 c. c. of benzene is allowed to run into a Grignard solution prepared from 6 g. magnesium filings, 22 c. c. brom-benzene and 60 c. c. of ether. The ether is distilled off and the mixture heated under reflux on a water-bath for 4 hours. After decomposition with ice and ammonium chloride, the mixture is extracted with ether, the ether solution washed with dilute hydrochloric acid, soda and water, dried over sodium sulphate and evaporated down. To remove the unchanged ester the residue is boiled for 30 minutes, under reflux, with a solution of 0.8 g. potassium hydroxide in 2 c. c. of water and 20 c. c. of alcohol. On working up as neutral product there is obtained $\Delta^{11:12}$ -3-hydroxy-nor-*cholenyl-diphenyl-carbinol* (Formula II) in crude form.

35 (b) The product mentioned is dissolved in 20 c. c. of pyridine, 17 c. c. of acetic anhydride added and the whole allowed to stand for 16 hours at room temperature. After evaporating down in vacuo, the residue is dissolved in ether, washed with dilute hydrochloric acid, soda solution and water, dried over sodium sulphate and evaporated down. The residue crystallizes out after standing for three days, from a little ether. The separation of crystals is completed as far as possible by the cautious addition of petroleum ether. Crystals of the mono-acetate, Formula III, M. Pt. 152-154° C., are obtained. For analysis the substance is again recrystallized from ether and petroleum ether. Colorless platelets, melting at 153-155° C., are obtained. Specific rotation

$$[\alpha]_D^{25} = +47.3^\circ \pm 3^\circ$$

(c=0.887 in acetone).

65 (c) 3.55 g. of the crystalline carbinol, Formula III, are boiled under reflux for 2 hours with 15 c. c. of glacial acetic acid. On working up crystals of the acetylated ethylene, Formula IV, M. Pt. 142-144° C., are obtained. For analysis the substance is again recrystallized from petroleum ether, when platelets melting at 144-145° C. are obtained.

(d) 2.4 g. of the acetylated ethylene (Formula IV) M. Pt. 142-144° C. are dissolved in 15 c. c. of glacial acetic acid (stable to chromic acid) and 5

c. c. of chloroform. The solution of 1.5 g. of chromium trioxide in 1 c. c. water and 7.5 c. c. glacial acetic acid is added, cooling gently, and the whole kept at a temperature of exactly 25° C. (internal temperature) for 2½ hours. The mixture is then evaporated down in vacuo, water added to the residue, the whole thoroughly extracted with ether and the ether solution washed several times with water. The mixture is then separated as usual with 2n soda solution, in the presence of ice, into neutral and acid components. The acid mostly separates off as the sparingly soluble sodium salt, whereas the unchanged ethylene compound can be regenerated from the neutral portion in the crystalline form.

The crude acid gives, from ether, crystals which melt at about 102–106° C., but are difficult to purify. The whole amount is therefore methylated with diazomethane and the methyl-ester obtained afterwards acetylated with pyridine and acetic anhydride. The methyl-ester (Formula VI) which has been purified in this way is further purified chromatographically, whereby elution of the product required from the aluminium oxide can be effected with petroleum ether, or more quickly with a mixture of equal parts of benzene and petroleum ether. The residues obtained after evaporating down the latter extracts give, on recrystallization from a mixture of ether and petroleum ether, colorless platelets which melt at 135–136° C. A side product can be extracted by afterwards washing the column with a mixture of benzene and ether; it melts indefinitely at about 162–168° C., but was not further investigated.

To determine the constitution, a sample of the substance melting at 135–136° C. was hydrogenated with platinum oxide in acetic acid, thus giving acetyl-nor-lithocholic-acid-methyl-ester (Formula VIII, M. Pt. 161–162° C., which proved to be identical with a sample prepared by degradation of lithocholic acid.

The ester (Formula VI) M. Pt. 135–136° C. has a specific rotation

$$[\alpha]_D^{15} = +56.2 \pm 2^\circ (c = 1.087 \text{ in acetone})$$

(e) 1 g. of the acetylated methyl-ester (Formula VI) is dissolved in 2.5 c. c. chloroform and 15 c. c. 1 per cent. hydrogen chloride in methyl alcohol and the whole allowed to stand for 16 hours at 20° C. After evaporating down in vacuo, the residue is dissolved in ether, the ether solution washed with dilute hydrochloric acid, soda solution and water, dried over sodium sulphate and concentrated. By adding petroleum ether $\Delta^{11:12}$ -3-hydroxy-nor-cholenic-acid-methyl-ester, Formula VII, M. Pt. 140–142° C., is obtained. A sample is recrystallized from a mixture of ether and petroleum ether and gives colorless crystals melting at 142–143° C.

(f) For further degradation to the bisnor-acid, a Grignard solution is prepared from 0.85 g. magnesium filings, 3 c. c. bromobenzene and 11 c. c. ether. To this mixture a solution of 900 mg. of the dry methyl-ester (Formula VII) in 8 c. c. absolute benzene is added and the mixture treated as described above. The crude product obtained is again boiled with alcoholic caustic potash and again worked up until the crude carbinol, Formula IX, is obtained. The latter did not form crystals. Acetylation with acetic anhydride and pyridine at room temperature (16 hours) gives the acetylated crude product, Formula X, which also does not crystallize out and is therefore boiled directly with 8 c. c. glacial acetic acid for 2 hours.

On working up, the crude ethylene compound, Formula XI, is obtained. It can be purified chromatographically and obtained as an almost colorless resin.

5 0.8 g. of this resin is dissolved in 1 c. c. chloroform and 3 c. c. glacial acetic acid and allowed to stand for 3 hours at 25–30° C. with the solution of 500 mg. chromium trioxide in 0.5 c. c. water and 2.5 c. c. glacial acetic acid. The mixture is then 10 separated into neutral and acid components. The latter are allowed to stand for 30 minutes with a solution of diazomethane in ether and the methyl-ester obtained is acetylated with 0.6 c. c. absolute pyridine and 0.4 c. c. acetic anhydride for 16 hours at room temperature. On working up, the 15 crude ester shown in Formula XIII is obtained, which is purified by chromatography and, on recrystallization from petroleum ether, forms colorless prisms melting at 101–102° C. Specific rotation

$$[\alpha]_D^{15} = +10.7^\circ \pm 2^\circ (c = 1.027 \text{ in acetone})$$

(g) Saponification of the acetylated methyl-ester, Formula XIII, with a 1 per cent. solution of 25 hydrogen chloride in methyl alcohol (see above) gives the free $\Delta^{11:12}$ -3-hydroxy-bisnor-cholenic-acid-methyl-ester, Formula XIV, which crystallizes in fine needles from a mixture of ether and petroleum ether and melts at 109–110° C.

(h) The hydroxy-ester, Formula XIV, is caused 30 to react in a similar way as described under a, b and c with phenyl-magnesium bromide (Formula XV), is acetylated (Formula XVI) and thoroughly boiled with glacial acetic acid (Formula XVII) 35 and then is oxidized—according to d—with excess chromic acid at about 25° C. $\Delta^{11:12}$ -3-acetoxy-ethiocholenic-acid, Formula XVIII, is obtained. Reaction with diazomethane gives the corresponding methyl-ester (Formula XIX) which 40 crystallizes from petroleum ether in needles, melts in the pure form at 99–100° C. and has the specific rotation

$$[\alpha]_D^{15} = +87.7^\circ \pm 2^\circ (c = 1.287 \text{ in acetone})$$

45 The $\Delta^{11:12}$ -3-hydroxy-ethiocholenic-acid-methyl-ester, Formula XX, obtained from the latter with a 1 per cent. solution of hydrogen chloride in methyl alcohol, melts at 124–126° C. and has a specific rotation

$$[\alpha]_D^{15} = +77.7^\circ \pm 2^\circ (c = 0.875 \text{ in acetone})$$

Instead of by acetylation the intermediate protection of the 3-hydroxyl group may be effected by conversion into any other derivative of the hydroxyl which upon hydrolysis can be reconverted into hydroxyl, e. g. any ester or ether group. Instead of by passing over the diphenyl carbinols the degradation may be effected by introducing any other hydrocarbon radical, so that for example the dimethyl, diethyl, dipropyl, dicyclohexyl carbinols and ethylenes are obtained. The tertiary carbinols and the corresponding ethylene compounds are equivalent for the oxidation step so that instead of the ethylene compounds—as described in this example—also the tertiary carbinols may be oxidized, e. g. with chromic acid.

If one starts from the $\Delta^{9:11}$ -3-hydroxy-cholenic-acid-methyl-ester instead of from the $\Delta^{11:12}$ -isomer, the corresponding degradation products, containing a double bond in 9:11-position are obtained.

Instead of the Wieland method described there may be used the Curtius or Hofmann method for this gradual degradation or the side chain may be degraded by radical oxidation.

What I claim is:

What I claim is:

1. In a process for the manufacture of compounds of the cyclopentanopolyhydrophenanthrene series, the step of subjecting a member selected from the class consisting of a compound of the series of cholanic acid, its lower homologues and the stereoisomers thereof, being substituted in ring A and containing a double bond in one of the positions 9:11 and 11:12, to oxidation by treating the same with chromic acid, whereby degradation of the side chain is effected.

2. Process for the manufacture of compounds of the cyclopentanopolypolyhydrophenanthrene series, comprising subjecting a member selected

from the class consisting of a compound of the series of cholic acid, its lower homologues and the stereoisomers thereof, being substituted in ring A and containing a double bond in one of the positions 9:11 and 11:12, to degradation of the side chain according to the Wieland process by reacting the same with an organo-metallic compound to produce the corresponding tertiary carbinol, and then oxidizing the product by treating the same with chromic acid, whereby the side chain degradation is effected.

3. Process for the manufacture of compounds of the cyclopentanopolyhydrophenanthrene series, comprising subjecting a member selected from the class consisting of a compound of the series of cholanic acid, its lower homologues and the stereoisomers thereof, being substituted in ring A and containing a double bond in one of the positions 9:11 and 11:12, to degradation of the side chain according to the Wieland process by reacting the same with an organo-metallic compound to produce the corresponding tertiary carbinol, dehydrating the carbinol by treating the same with acetic anhydride, and oxidizing the resultant ethylene compound by treating the same with chromic acid, whereby the side chain degradation is effected.

4. Process for the manufacture of compounds of the cyclopentanopolyydrophenanthrene series, comprising subjecting a member selected from the class consisting of a compound of the series of cholic acid, its lower homologues and the stereoisomers thereof, being substituted in ring A and containing a double bond in one of the positions 9:11 and 11:12, to a radical degradation of the side chain by treating the same with chromic acid with intermediate protection of hydroxyl groups and carbon double bonds.

40 5. A compound of the 10,13-dimethyl-cyclopentanopolyhydrophenanthrene series containing a double bond in one of the positions 9:11 and 11:12 and, in 17-position, the substituent

wherein n stands for a whole number from 0 to 2, and R stands for a hydrocarbon radical.

6. A compound of the 10,13-dimethyl-cyclopentanopolyyhydrophenanthrene series containing a double bond in one of the positions 9:11 and 11:12 and, in 17-position, the substituent

wherein n stands for a whole number from 0 to 2, and R stands for a hydrocarbon radical, and also containing in the 3-position a member selected from the group consisting of hydroxyl and a radical which upon hydrolysis is converted into hydroxyl.

7. $\Delta^{11:12}$ -3-acetoxy-*etio*cholenic acid.

TADEUS REICHSTEIN.
